UNITED STATES PATENT OFFICE.

JOHN SIVAK, ALEXANDER NAGY, AND LADISLAUS BANDURAY, OF NEW YORK, N. Y.

HYGIENIC TOILET-SEAT.

1,142,374.

Specification of Letters Patent. Patented June 8, 1915.

Application filed July 7, 1914. Serial No. 849,401.

To all whom it may concern:

Be it known that we, JOHN SIVAK, a citizen of the United States, and ALEXANDER NAGY and LADISLAUS BANDURAY, both subjects of the King of Hungary, residing at New York, in the county of New York and State of New York, have invented new and useful Improvements in Hygienic Toilet Seats, of which the following is a specification.

Our invention relates to a hygienic toilet seat and its principal object is to provide a device whereby the user of a toilet—especially in public localities—may never come into contact with the surface touched by any preceding user of the toilet.

A further object of our invention is to provide a toilet seat that is always clean and proper for use and cannot be soiled by urine or any other foreign substance.

A final object of our invention resides in the particular arrangement and combination of parts hereinafter described.

In the accompanying drawing:—Figure 1 is a vertical sectional view of the entire arrangement, taken on the line 1—1 of Fig. 2 and looking in the direction indicated by the arrows. Fig. 2 is a plan view of the device, with certain parts partly removed and other parts shown in dotted lines, to afford a better view of the arrangement of parts in respect to each other. Fig. 3 is a cross sectional view of the mechanism. Fig. 4 is a cross sectional detail view.

Throughout the separate views the same part is designated by the same reference character.

Referring more particularly to the drawing, 1 designates a bowl of a toilet as in common use. Fixed to it by hinges 2—2 are a pair of seat sections 3—3 made of wood or other suitable material, preferably of the shape in plan as shown in Fig. 2. This pair of flaps in conjunction with the tie member 4 connecting them at the fore ends, form the seat. A pair of drums such as 5 are mounted on an axis 6, said axis loosely journaled in the sides of a box 7 placed conveniently in the rear of the seat, either on a level with the same or below it if there is a lack of space. Rolls of paper such as 8 are placed on each of the drums 5 and the strips of paper, passing through slots in the box 7, are drawn over each of the flaps 3 and through slots 9—9 into another box 10 placed in front of the bowl, where the

strips of paper are wound up on other drums such as 11 by means of a mechanism, consisting of: a rack bar 12 fixed hingedly to the bottom of the tie member 4 and guided by lugs such as 13, engaging a pinion 14 fixedly mounted on a shaft 15, on which shaft 15 are also mounted fixedly a set of springs such as 16 fastened with their other ends to the back of the box 10 and a ratchet such as 17 at either end of the shaft 15 also fixedly mounted and pressed by springs 18—18 toward corresponding ratchets 19—19 with which the ratchets 17—17 engage. The ratchets 19—19 are cast in one piece with pinions 20—20, respectively, the pinions 20—20 engaging intermediate pinions 21—21 and these in turn the pinions 22—22 which are fixedly mounted on shaft 23. The geared wheels 20—20 are loosely mounted on the shaft 15 and can only turn from left to right, when the ratchets 17—17 and 19—19 engage each other, respectively, in a forcible manner, whereas in the contrary direction said ratchets slide on each other and the geared wheels 20—20 are prevented from turning by dogs such as 24.

In its normal position the seat will be held aloft from the bowl by two springs, one on each side, such as 25, journaled in the sides of the bowl 1. When a person sits down on the seat, the rack bar is pressed down by the person's weight and puts the pinion 14 in motion, thereby turning the shaft 15 and winding up the springs 16—16. The rest of the mechanism stands still during this period, whereas, when the person occupying the seat stands up and relieves the seat of the weight, the action of the springs 16—16, aided by that of the springs 25—25, lifts the seat and at the same time causes the shaft 15 to turn in the contrary sense of that before mentioned, whereby the gear train 20—21—22 is set in motion and the drums 11 wind up the paper suitably fastened thereon. The gear is so calculated that with each performance as above described sufficient paper be wound up to provide a fresh cover over the entire seat.

The drums 11 when filled with used paper can be removed by taking out the shaft 23 from its bearings in the box, 10, so arranged, or the paper may simply be cut off from the drums when required.

The paper used in this device may also be lined with cloth or other suitable fabric for the purpose of greater strength.

Having thus described our invention, what we claim is:—

The combination with a toilet seat comprising two seat sections connected at their front ends by a horizontal tie member and normally kept above the toilet vase by means of springs mounted on the rim thereof,—of a vertical rack secured to the bottom part of said tie-member, a box placed in front of 10 said toilet vase, a horizontal shaft journaled in the sides of said box, a pinion rigidly mounted on said shaft in engagement with said vertical rack, spiral springs attached with their inner ends to said shaft and with 15 their outer ends to said box, adapted to be wound up on said shaft and thereby put under tension, by means of said rack and pinion, when said seat sections are pressed down, gears loosely mounted on said shaft, 20 one at either end thereof, ratchets carried by said shaft adapted to engage said gears when said shaft is rotated by said springs and out of engagement with same while the springs are put under tension by the rack

pinion, another shaft journaled in the sides 25 of said box below said first mentioned shaft, parallel thereto, carrying gears at either end in engagement with said first mentioned gears and adapted to be rotated thereby,— and a pair of drums rigidly mounted on said 30 second mentioned shaft in vertical alignment with said seat sections, adapted to wind up thereon individual strips of paper drawn over said seat sections from rolls placed therebehind, whenever said seat sections are raised from the toilet vase by means of said springs mounted on the rims thereof, substantially as and for the purpose set forth.

In testimony whereof we affix our signatures in the presence of two witnesses.

JOHN SIVAK.
ALEXANDER NAGY.
LADISLAUS BANDURAY.
